Walter A. Holden.

UNITED STATES PATENT OFFICE.

WALTER A. HOLDEN, OF ANSONIA, CONNECTICUT, ASSIGNOR TO THE ROBERT N. BASSETT COMPANY, OF SHELTON, CONNECTICUT, A CORPORATION OF CONNECTICUT.

GARMENT-SUPPORTER.

1,130,821.

Specification of Letters Patent.

Patented Mar. 9, 1915.

Application filed February 25, 1913. Serial No. 750,533.

To all whom it may concern:

Be it known that I, WALTER A. HOLDEN, a citizen of the United States, residing at Ansonia, in the county of New Haven and State of Connecticut, have invented a certain new and useful Improvement in Garment-Supporters, of which the following is a specification.

My invention relates to garment supporters of the class in which the garment clasp, which is usually of the loop and button type, is made fast or permanently attached to the supporting strap or webbing; and its object is to provide a device of this character having a minimum number of parts and in which the expedient of sewing or stitching can be entirely eliminated. I attain this and other objects of my invention in the preferred embodiment thereof set forth in the following description and the accompanying drawing in which like reference characters refer to corresponding parts.

In the drawing: Figure 1 is a front view of my device, a portion of the webbing and loop being broken away; Fig. 2, a central, longitudinal section taken on line $x-x$ of Fig. 1; Fig. 3, a longitudinal, sectional view of the parts in position to be assembled, and Fig. 4, a vertical longitudinal section of a modification.

My invention generally consists of the supporting strap A carrying at its lower extremity the connecting piece or binder B, which latter in turn carries the loop C and button tab D. A button E is mounted on the lower extremity of the tab D. The supporting strap A, wire loop C and button tab D are of the usual construction in garment supporters of this character, the novelty in my invention residing in the construction of the connecting piece which binds all of the parts together. This connecting piece B consists of a body plate 2 having side lugs 3, 3, and a tongue 4. This tongue 4 is usually narrower than the body plate 2, which latter is preferably of the same width as the supporting strap A. The connecting piece is further provided with a slot disposed transversely thereof near to where the tongue 4 joins the body plate 2, and this slot 6 is of a length equal to or greater than that of the tab D. The binder or connecting piece B is suitably bent and struck up out of sheet metal so that its side lugs 3, 3 and tongue 4 project at an angle thereto, as shown in Fig.

3, but when the device is assembled these parts are folded toward the body plate 2 in a manner which will be hereinafter described.

The device is assembled in two operations. During the first operation, which is by hand, the free extremity 7 of the tab D is inserted upwardly through the slot 6 until its edge 10 is substantially coincident with the end 5 of the tongue 4, in which position it is held by the fingers against the inner face of the tongue 4 while the top bars 9, 9 of the loop C are passed over both the tongue and tab. The loop C is preferably made resilient so that its opening in under the top bars is of such a width that it can be sprung or spread slightly when the top bars are passed over the tongue. This resilient action causes the top bars to clip or frictionally engage the side edges of the tongue, so that when the top bars 9, 9 are drawn down into the angle formed between the tongue 4 and the body plate 2 the extremity 7 of the tab is held against the inside of the tongue thereby preventing the tab from falling out during the process of assembling. This enables so much of the assembling as has already been described to be performed away from the machine, which is utilized in the second operation. After the parts are thus assembled the connecting piece B is placed in a suitable machine wherein the top bars 9, 9 of the loop are raised sufficiently to permit the insertion of the extremity 8 of the supporting strap in under the top bars of the loop, after which the top bars are again drawn back into the angle formed between the tongue and the body plate. The machine is then operated to roll the tongue 4 and extremity 7 of the tab around the top bars 9, 9 of the loop so that their extremities or edges 5 and 10 respectively are pressed against the supporting strap just as the latter passes behind the top bars 9, 9. At the same time the machine presses down the side lugs 3, 3 against the supporting strap A so that the latter is securely confined or gripped between the body plate 2 and the side lugs 3, 3. In this manner not only the loop and button tab but also the supporting strap is swedged to the binder B so that the parts cannot become disassembled without destroying the device, thereby effecting a permanent and secure connection between all of the parts. It should be noticed that the slot 6 can be so

disposed that the extremity 7 of the tab will bind around one edge of the slot in passing therethrough. It should be further noticed that both the front and back of the connecting piece present flush surfaces with the supporting strap so that the device is flat and compact carrying a roll at its lower extremity. It is not necessary that the tab should be passed down in back of the loop, as shown in Fig. 2, since the same after passing through the slot 6 may be passed down the opposite side of the loop as shown in Fig. 4, thereby enabling the exposed side of the connecting piece to be utilized as a front. In such a case the tab will be reversed so that the button E will appear on the other side thereof before the extremity 7 is passed into the slot 6. Of course the connecting piece may be stamped to present various designs for the purpose of enhancing its appearance. It should be observed that the extremity 8 of the supporting strap A need not necessarily be passed down around the side of the top bars 9, 9 of the loop since it may terminate immediately above the edge 5 so as to be confined alone by the side lugs 3, 3 or in some other manner wherein it is made fast to the connecting piece.

While the device above described is the preferred form of my invention yet the same is susceptible to such modification as may

come within the scope of my appended claims.

Having now described my invention what I desire to claim and protect by Letters Patent is:

1. A garment supporter consisting of a supporting strap having a sheet metal binder wedged on to its lower extremity, a button loop and a button tab, the lower end of said supporting strap and the upper end of said tab being rolled around the top side of said loop, and the said binder being provided with a depending tongue which is rolled around the top side of said loop to fasten the said supporting strap, tab and loop to said binder.

2. A garment supporter consisting of a supporting strap having a sheet metal binder wedged on to the lower extremity thereof, a button loop and a button tab, the said binder being provided with a depending tongue and a transversely disposed slot through which the tab end is inserted, and the said tongue being folded around the top side of said loop to engage said tab end to fasten said loop and tab to said binder.

WALTER A. HOLDEN.
